(57) **CLAIM**

The ornamental design for a movement assistance device, as shown and described.

DESCRIPTION

FIG. 1 is a perspective view of a movement assistance device showing my new design;

FIG. 2 is a front view thereof;

FIG. 3 is left side view thereof, the right side view being a mirror image thereof;

FIG. 4 is rear view thereof;

FIG. 5 is a top view thereof;

FIG. 6 is a bottom view thereof;

FIG. 7 is a perspective view thereof, shown in a sitting position;

FIG. 8 is a front view thereof, shown in a sitting position;

FIG. 9 is left side view thereof, shown in a sitting position, the right side view being a mirror image thereof;

FIG. 10 is rear view thereof, shown in a sitting position;

FIG. 11 is a top view thereof, shown in a sitting position; and,

FIG. 12 is a bottom view thereof, shown in a sitting position. The broken lines shown in the drawings represent portions of the movement assistance device that form no part of the claimed design.

It is understood that the appearance of any part of the article not shown in the drawing or described in the specification forms no part of the claimed design.
